United States Patent Office

Des. 205,996
Patented Oct. 18, 1966

205,996

AUTOMOBILE SERVICE STATION

Albert Shotmeyer, Wyckoff, N.J.
(Shotmeyer Brothers Company, Hawthorne, N.J.)

Filed Mar. 16, 1966, Ser. No. 1,491

Term of patent 14 years

(Cl. D13—1)

FIG. 1

FIG. 2FIG. 3FIG. 1 is a perspective view of an automobile service station showing my new design;

FIG. 2 is a top plan view; and

FIG. 3 is a sectional view taken along the line 3-3 of FIG. 1.

I claim:

The ornamental design for an automobile service station, as shown and described.
